UNITED STATES PATENT OFFICE.

ALEXANDER C. SLADKY AND JOSEPH SLADKY, OF MILWAUKEE, WISCONSIN, ASSIGNEES TO NATIONAL ENAMELING & STAMPING CO., INC., OF MILWAUKEE, WISCONSIN.

CAMP COOKSTOVE.

Application filed March 14, 1927. Serial No. 175,124.

This invention relates to camp cook stoves. Objects of this invention are to provide a novel form of camp cook stove or portable folding stove which is so constructed that the gasoline or fuel tank together with the projecting parts may be detached and readily stored within the body of the stove, and which may be readily coupled to the burner when it is desired to operate the stove without requiring a sliding, fitting or threading of the projecting tube through an aperture or into a socket, but instead, in which a butt joint is employed and is held tight inherently by the construction of the apparatus, the weight of the tank holding the butt joint tight.

Further objects are to provide a simple form of stove which may be readily constructed and which is adapted to furnish two or more burners with selective control, whereby one or more of the burners may be used at a time.

An embodiment of the invention is shown in the accompanying drawings in which:

Figure 1 is a plan view of the stove with parts broken away showing the cover open;

Figure 2 is a view partly in section showing the device in elevation;

Figure 3 is a transverse sectional view showing the tank in stored position;

Figure 4 is an enlarged detail of the butt joint, such view being partly in section;

Figure 5 is a sectional view approximately on the line 5—5 of Figure 4.

Referring to the drawings, it will be seen that the stove comprises a box-like metal housing or body portion 1 within which the parts are placed. This body portion is provided with inwardly turned lugs or flanges 2 adapted to receive a movable or detachable grate of any suitable construction, such grate, however, being omitted for the sake of clearness. The body portion is provided with a hingedly mounted sheet metal top 3 which is adapted to be opened out when the stove is in use or to be closed to completely house the mechanism. Any suitable fastening means may be provided for the cover, such means, however, being omitted as they may be of the conventional type.

The body portion carries a burner which is rigidly attached and which consists of an upwardly and longitudinally curving mixing tube 4 which opens downwardly into a

manifold or distributor pipe 5, such pipe leading upwardly to the main burner 6 and an auxiliary burner 7. The main burner remains in communication with the manifold or supply pipe 5 for the combustible mixture, whereas the auxiliary burner 7 may be cut off from the manifold 5 by means of a gate valve consisting of a disc-like member 8 pivotally mounted upon the burner, as indicated at 9. This disc-like valve is provided with an aperture 10 adapted to register with the aperture opening into the burner when the parts are in the position shown in Figure 1. In order to manipulate this valve, an outwardly projecting lever 11 is formed, preferably integrally with the valve 8 and projects outwardly through the casing, such lever being provided with an upturned thumb-piece or manipulating portion 12. In order to protect the rock lever 11 from blows which would tend to distort it, the body of the casing 1 is bowed outwardly, as indicated at 13 along the arc of a circle, as most clearly shown in Figure 1, and a slot is provided through which the lever 11 projects. Thus, the manipulating portion of the lever is at all times in close relation to the body of the casing and can not therefore be readily distorted.

The burner structure is provided with an entrance opening 14 (see Figure 4) into which the gas is forced as it passes through the needle valve opening 15, such opening being controlled by a needle valve 16 carried by a valve rod 17. It is adjusted in the usual manner by means of a hand wheel 18, as shown in Figures 1 and 2. The air passes upwardly through the open bottom, downwardly projecting portion 19 of the burner structure. A heating cup 20 is formed integrally with the burner structure, as shown in Figures 4 and 5, and is adapted to receive some of the liquid fuel to initially heat the generator tube 21. It is to be noted particularly that the generator tube 21 terminates in an abrupt shoulder or flange 22 for a purpose hereinafter to appear. The other end of the generator tube communicates with the tank through the medium of the supply tube 23 which extends downwardly into the tank.

The shoulder or flange 22 of the generator tube has its flat face directly contacting with a flat machined face 23 formed on the front end of the mixing tube 4 of the burner. The

flat faces of the shoulder 22 and of the burner mixing tube 4 thus constitute a butt joint. The means for holding this butt joint tightly closed consists of a slightly springy 5 hook-shaped clip 24 secured in any suitable manner as by means of screws, for instance, to the burner tube. This hook-shaped clip is provided with the upwardly extending hooked portion (see Figure 4) which engages 10 over the top edge of the flange 22 of the mixing tube. The lower portion of the flange 22 of such tube contacts at two spaced points, as indicated at 25, with the sides of the heating cup, as most clearly shown in Figure 5. 15 Thus, a three-point contact is provided for the flange 22 and it is securely held against displacement.

It is to be noted particularly from Figures 2 and 4, that the heating cup is of elongated 20 rectangular construction. This mode of forming the parts facilitates the positioning of the generator tube and its flange 22, as shown in dotted and full lines in Figure 4, and as will be described in greater detail 25 hereinafter.

The fuel tank 26 (see Figure 2) is adapted to be supported by means of a pair of curved spaced arms 27 formed of strap metal and preferably braced by means of 30 the member 28. These arms are hinged, as indicated at 29, to the end of the body portion 1 of the stove, as shown in Figure 2, and when not holding the tank are adapted to be swung inwardly into the dotted line position shown in Figure 2. Further, the tank, as stated previously, is adapted to be stored within the body portion, particularly as 35 shown in Figure 2. When so stored, the tank 26 rests upon the bottom of the body portion 1, and its manipulating hand wheel 18 bears against an inwardly turned portion 30 of the body of the stove. The other end, namely, the flange 22, rests upon a small shelf 31 formed by a bracing member 32 located 40 within the stove.

In using the device, the fuel tank is lifted from within the housing or compartment 1 and is held with its generator tube and flange 22 in the dotted line position shown in 45 Figure 4. Some fuel is allowed to flow into the heating cup 20 and thereafter the upper edge of the flange 22 is hooked beneath clip 24 and the parts are rocked into the full line position shown in Figure 4, and also 50 shown in Figures 1 and 2. It is to be noted that the body portion is provided with an open topped notch 33 in its end wall into which the mixing tube 21 rocks. The outwardly rocked arms 22 of the frame support 55 the fuel tank, as shown in Figure 2. This downward rocking of the parts causes the flange 22 to rock about its upper edge beneath the clip 24 and to ride upon the marginal or side edges of the heating cup, thus 60 tightly forcing itself against the flat face 23

of the burner structure and maintaining the tight butt joint, previously discussed.

In this connection, it is to be noted that the center part of the flange 22 is slightly cut out, as indicated at 34 in Figure 4, so as 70 to protect the point of the needle valve from inadvertent contact with any object during positioning and removal of the parts. It is to be noted also that a slight or shallow annular groove 35 is formed in the flat face 75 of the flange 22 of the mixing tube.

It will be seen that a novel form of camp stove has been provided in which no threading of the generator tube through apertures and into sockets is required, but instead, in 80 which a butt joint is employed inherently held tight by the weight of the fuel tank.

Further, it will be seen that the device is so made that the fuel tank may be freely rocked into operative position and that the generator tube is freely received within an open topped notch in the end wall of the casing.

It will be seen further that no skill or care is required on the part of the operator in 90 assembling the parts as accurate fits are not required. Obviously, if the flange 22 is slightly displaced laterally, it will correctly position itself, as shown in Figure 5, due to its three point support.

It is to be distinctly understood that the term "camp stove" is intended to cover not only the stoves used solely for camping, but other collapsible or portable stoves of this 100 general type.

Although the invention has been described in considerable detail, such description is intended as illustrative rather than limiting as the invention may be variously embodied and as the scope of such invention is to be 105 determined as claimed.

We claim:

1. In a camp stove, the combination of a burner structure provided with a mixing tube, a fuel tank having a projecting generator tube provided with a flange for abutting engagement with said mixing tube, a hooked portion adjacent said mixing tube for hooking over said flange, and means for supporting the lower portion of said flange, whereby the weight of the fuel tank causes the flange to tightly abut against said mixing tube.

2. In a camp stove, the combination of a burner structure provided with a mixing tube, a fuel tank having a projecting generator tube provided with a flange for abutting engagement with said mixing tube, a hooked portion adjacent said mixing tube for hooking over said flange, and means for supporting the lower portion of said flange, at two spaced points, whereby the weight of the fuel tank causes the flange to tightly abut against said mixing tube.

3. In a camp stove, the combination of a

burner structure having a mixing tube provided with a flat face, a detachable fuel tank having a projecting generator tube having a flange, and means for pivotally supporting said flange, whereby the weight of the fuel tank rocks the flange into binding abutting engagement with the flat face of said mixing tube.

4. In a camp stove, the combination of a burner structure having a mixing tube, a detachable fuel tank having a projecting generator tube extending from a point spaced from both ends of the tank and terminating in a flange provided with a flat face, said burner structure having a flat face for contacting with the flat face of said flange, a clip for holding the upper portion of the flange in temporary contact with the burner structure, and a heating cup positioned adjacent the lower portion of the flat face of said burner structure, whereby the flange may be rocked by the weight of the tank into binding abutting engagement with the flat face of the burner structure.
5. In a camp stove, the combination of a casing, a burner carried within said casing and having a mixing tube provided with a flat face and with a heating cup below said flat face, a fuel tank having a projecting generator tube terminating in a flange provided with a flat face, means carried by said mixing tube adjacent the upper portion of the flat face for interlocking with the flange of the generator tube, whereby said flange may be interlocked with said means and may be rocked into abutting binding contact with the flat face of the mixing tube, said casing having an upwardly opening notch into which the generator tube is adapted to be rocked.
6. In a camp stove, the combination of a casing, a burner carried within said casing

and having a mixing tube provided with a flat face and with a heating cup below said flat face, a fuel tank having a projecting generator tube terminating in a flange provided with a flat face, means carried by said mixing tube adjacent the upper portion of the flat face for interlocking with the flange of the generator tube, whereby said flange may be interlocked with said means and may be rocked into abutting binding contact with the flat face of the mixing tube, said casing having an upwardly opening notch into which the generator tube is adapted to be rocked, and a pivotally mounted support for said fuel tank, said support being rotatable into or out of the said casing.

7. In a camp stove, the combination of a burner structure having a main burner and an auxiliary burner and having a common mixing tube provided with a flat face and with a heating cup located below said flat face, a hook-like member carried by said mixing tube adjacent the upper portion of said flat face, a gate valve for cutting off the auxiliary burner from communication with the common mixing tube, a fuel tank provided with a projecting generator tube terminating in a flange having a flat face, whereby said flange may be positioned beneath said hook-like member and rocked upon said heating cup into binding abutting engagement with the flat face of the mixing tube, the weight of the tank maintaining the binding relation between the flat faces.

In testimony that we claim the foregoing we have hereunto set our hands at Milwaukee, in the county of Milwaukee and State of Wisconsin.
